UNITED STATES PATENT OFFICE.

PHILO C. EWART, OF CINCINNATI, OHIO; MYRA V. EWART EXECUTRIX OF
SAID PHILO C. EWART, DECEASED.

CAR-COUPING.

SPECIFICATION forming part of Letters Patent No. 728,888, dated May 26, 1903.

Application filed June 7, 1900. Serial No. 19,452. (No model.)

To all whom it may concern:

Be it known that I, PHILO C. EWART, a citizen of the United States, residing at Cincinnati, in the county of Hamilton and State of Ohio, have invented certain new and useful Improvements in Car-Couplers, of which the following is a specification.

My invention relates to automatic car-couplers; and its objects are to furnish improved coupling and uncoupling mechanism, mechanism whereby the coupler is positively locked against uncoupling when under strain, and mechanism whereby the coupling-hook is automatically locked in its uncoupled position and automatically released upon coupling impact.

The invention consists in the combination and arrangements of parts hereinafter set forth and claimed.

20 In the drawings, Figure 1 is a perspective view of a coupler embodying my invention attached to the end of a car; Fig. 2, a front elevation of the coupler detached; Fig. 3, a horizontal section of the coupler when not under strain with parts broken away to show the unlocking device; Fig. 4, a vertical section on line 4-4 of Fig. 3; Fig. 5, a horizontal section of the coupler in its uncoupling position; Fig. 6, a vertical section on line 6-6 of Fig. 5; Fig. 7, a horizontal section showing the coupler under strain and locked against uncoupling; Fig. 8, a side elevation of the uncoupling device, on an enlarged scale; Fig. 9, a perspective view of the uncoupling device, and Fig. 10 a perspective view of the outer end of the socket for the uncoupling device.

Reference-letter A denotes the buffer-head; B, the coupling-hook; C, the draft-stem; D, the unlocking-shaft, and E the uncoupling lever. The buffer-head A is pivoted to the draft-stem C by a pin a . At a' it is provided with sockets to receive the coupling-springs b . The coupling-hook B is pivoted to the buffer-head and draft-stem by pin a , and its shank is extended at b' to engage springs b , which press the hooks to coupling positions. The pivot-hole b^2 in hook B is elongated, so as to permit of a slight longitudinal movement of the hook relatively to the head. The

hook is provided with shoulders b^3 , adapted to engage ledges a^2 on the buffer-head, so that when the hook is drawn forward relatively to the head the shoulders b^3 engage the ledges on the head, positively locking the hook 55 against swinging out and becoming uncoupled. When the pulling strain on the hook is relieved, the tension of springs b throws the hook back, disengaging shoulders b^3 and ledges a^2 and leaving the hook free to be 60 swung back against the pressure of springs b , and so uncoupled. Although I prefer to use the shoulders b^3 on the hook, they may be omitted, and the hook when under pulling strain will be held against uncoupling movement by the ledge a^2 on the buffer-head. In order to swing the hook back for uncoupling, the shaft D is rotatably mounted on the buffer-head and provided with a screw-cam d , adapted to contact with the inner edge b^4 of the 70 neck of the hook, so that when the shaft D is properly rotated the edge b^4 of hook B travels up the screw-face d' of cam d , swinging the hook back, as shown in Fig. 5. It will be seen that when the screw-cam first contacts with the edge of the hook-neck its tendency is to force the hook back into its extreme rear position and unlock the hook in case the springs b' should for any reason fail to act. The shaft D is provided with a projection d^2 , 75 adapted to engage with a stop a^3 on the head at the mouth of the bearing or socket in which shaft D is mounted. The stop a^3 consists of an inclined face a^4 , up which the projection d^2 travels during the uncoupling rotation of 80 shaft D, thereby slightly withdrawing the shaft from its socket, and a shoulder a^5 , behind which the projection is drawn by the tension of springs b' , thus locking the hook in its uncoupled position, as shown in Fig. 5. 90

The shaft D is provided with a shoulder d^3 , so related to the hook B that when the hook is locked in its uncoupled position the rear of the neck is in close proximity to the shoulder, so that a slight movement of the hook 95 outwardly will move the shaft D correspondingly, disengage projection d^2 from shoulder a^5 , and permit the closing of the hook. The shape of the hook is such that when thus locked in its uncoupling position its point b^6 projects 100

slightly into the mouth of the buffer-head. Thus it will be seen that if coupling is attempted while the hook is locked in its uncoupled position the point b^5 of the hook will be struck by the incoming hook and forced back sufficiently to dislodge projection d^2 and permit coupling. The operative rotation of shaft D is accomplished by means of crank-shaft E engaging eye d^4 therein and extending toward the side of the car, where its handle e is accessible without going between the cars.

I claim—

1. The combination, in a car-coupling, of a buffer-head; a coupling-hook adapted to swing relatively to the head and capable of longitudinal movement relatively thereto, upon application of the strain; and locking elements on the hook and head, normally free from engagement, but adapted to engage upon the longitudinal movement of one relatively to the other, to prevent swinging of the coupling-hook, substantially as and for the purpose set forth. 15
2. The combination, in a car-coupling, of a buffer-head; a coupling-hook having a pivotal mounting and capable of longitudinal movement relatively thereto, upon application of the strain; and locking elements on the hook 20 and head, normally free from engagement, but adapted to engage upon the longitudinal movement of one relatively to the other, to prevent swinging of the coupling-hook, substantially as and for the purpose set forth. 25
3. The combination, in a car-coupling, of a buffer-head, a coupling-hook pivoted in the head and capable of longitudinal movement relatively thereto; yielding means pressing the hook to coupling position; and locking 30 elements on the hook and head, adapted to engage upon the longitudinal movement of one relatively to the other, substantially as and for the purpose set forth. 35
4. The combination, in a car-coupling, of a buffer-head; a coupling-hook having a pivotal mounting through a slot elongated in the direction of strain; and locking elements on the hook and head, normally free from engagement, but adapted to engage upon the longitudinal 45 movement of one relatively to the other, substantially as and for the purpose set forth. 50
5. The combination, in a car-coupling, of a buffer-head pivotally connected with the car; a coupling-hook having a pivotal mounting through a slot elongated in the direction of strain; and locking elements on the hook and head, normally free from engagement, but adapted to engage upon the longitudinal 55 movement of one relatively to the other, substantially as and for the purpose set forth. 60
6. The combination, in a car-coupling, of a buffer-head, a coupling-hook adapted to swing relatively to the head, and capable of longitudinal movement relatively to the head; locking elements on the head and hook adapted 65

to engage upon the longitudinal movement of one relatively to the other, and yielding means for pressing the hook to coupling position, substantially as and for the purpose set forth. 70

7. The combination, in a car-coupling, of a buffer-head; a coupling-hook having a pivotal connection with the buffer-head through a slot elongated in the direction of the line of strain, locking elements on the head and hook adapted to engage upon the longitudinal movement of one relatively to the other, and yielding means for pressing the hook to coupling position, substantially as and for the purpose set forth. 80

8. The combination, in a car-coupling, of a buffer-head; a coupling-hook adapted to swing relatively to the head, and capable of longitudinal movement relatively to the head, yielding means for pressing the hook to coupling position; locking elements on the hook and head adapted to engage upon the longitudinal movement of one relatively to the other; means for moving the head or hook to disengage the locking elements, substantially as and for the purpose set forth. 85 90

9. The combination, in a car-coupling, of a buffer-head; a coupling-hook adapted to swing relatively to the head, and capable of longitudinal movement relatively to the head, yielding means for pressing the hook to coupling position; locking elements on the hook and head adapted to engage upon the longitudinal movement of one relatively to the other; means for moving the head or hook to disengage the locking elements; a screw-cam connection between the hook and head, and means for actuating the screw-cam to withdraw the hook, substantially as and for the purpose set forth. 95 100

10. The combination, in a car-coupling, of a buffer-head; a coupling-hook adapted to swing relatively to the head, and capable of longitudinal movement relatively to the head, yielding means for pressing the hook to coupling position; locking elements on the hook and head adapted to engage upon the longitudinal movement, of one relatively to the other; means for moving the head or hook to disengage the locking elements; a shaft mounted to rotate in the head; a screw-cam on the shaft adapted to engage the hook and withdraw it, substantially as and for the purpose set forth. 110 115

11. The combination, in a car-coupling, of a buffer-head; a coupling-hook adapted to swing relatively to the head, and capable of longitudinal movement relatively to the head; yielding means for pressing the hook to coupling position; locking elements on the hook and head adapted to engage upon the longitudinal movement of one relatively to the other; means for moving the head or hook to disengage these locking elements; a rotatable shaft mounted in the head, a screw-cam on the shaft, adapted to engage the hook and with- 120 125 130

draw it; a stop on the head, a projection on the shaft adapted to engage the stop and lock the hook in its uncoupling position, and means for rotating the shaft, substantially as and for the purpose set forth.

12. The combination, in a car-coupling, of a buffer-head; a coupling-hook adapted to swing relatively to the head, and capable of longitudinal movement relatively to the head, yielding means pressing the hook to coupling position; locking elements on the hook and head adapted to engage upon the longitudinal movement, of one relatively to the other; means for moving the head or hook to disengage the locking elements; a rotatable shaft mounted in the head; a screw-cam on the shaft, adapted to engage the hook and withdraw it; a stop on the head; a projection on the shaft adapted to engage the stop and lock the hook in its uncoupling position; a shoulder on the shaft so related to the hook as to be in contact or close proximity thereto when the hook is locked in its uncoupling position, so that a slight movement of the hook will dislodge the projection from the stop; and means for rotating the shaft, substantially as and for the purpose set forth.

13. The combination, in a car-coupling, of a buffer-head; a coupling-hook adapted to swing relatively to the head and capable of longitudinal movement; a spring adapted to engage the shank of the hook and press the hook to coupling position; locking elements on the hook and head adapted to engage upon the longitudinal movement of one relatively to the other; yielding means for moving the locking elements out of engagement for swinging the hook relatively to the head, substantially as and for the purpose set forth.

14. The combination, in a car-coupling, of a buffer-head, a coupling-hook adapted to swing relatively to the head and capable of longitudinal movement; a spring adapted to engage the shank of the hook and press the hook to coupling position; shoulders b^3 on the hook adapted to engage edges a^2 of the buffer-head upon forward longitudinal movement of the hook relatively to the head; yielding means for moving the locking elements out of engagement, and means for swinging the hook relatively to the head, substantially as and for the purpose set forth.

15. The combination in a car-coupling, of a buffer-head; a coupling-hook adapted to swing relatively to the head; a shaft, engaging elements on the hook, head and shaft whereby rotation of the shaft engages the hook forward of the pivot and withdraws it, and means for rotating the shaft, substantially as and for the purpose set forth.

16. The combination in a car-coupling of a buffer-head; a coupling-hook adapted to swing relatively to the head; a shaft; an engagement between the shaft and hook whereby rotation of the shaft withdraws the hook but

leaves the hook free for further withdrawal without affecting the shaft, and the shaft free to return to its inoperative position without affecting the hook; means for locking the shaft in position with the hook in uncoupling position; means on the shaft and hook whereby further outward movement of the hook beyond its uncoupling position unlocks the shaft; means for returning the shaft to its inoperative position, and means for rotating the shaft, substantially as and for the purpose set forth. 70

17. The combination, in a car-coupling, of a buffer-head; a coupling-hook pivoted in the head; a shaft rotatably mounted in the head; a screw-cam on the shaft engaging the shank of the hook forward of the pivot; and means for rotating the shaft, substantially as and for the purpose set forth. 80

18. The combination, in a car-coupling, of a buffer-head; a coupling-hook adapted to swing relatively to the head and capable of longitudinal movement relatively to the head; locking elements on the hook and head adapted to engage upon the longitudinal movement of one relatively to the other; a shaft mounted in the head; a screw-cam on the shaft adapted to engage the hook, force it back longitudinally from the position assumed under strain, and withdraw it from its coupling position, and means for rotating the shaft, substantially as and for the purpose set forth. 90

19. The combination in a car-coupling, of a pivoted buffer-head; a coupling-hook pivoted to the buffer-head pivot; a shaft rotatably mounted in the head; a screw-cam on the shaft engaging the shank of the hook forward of the pivot; and means for rotating the shaft, substantially as and for the purpose set forth. 100

20. The combination, in a car-coupling, of a stem, a buffer-head pivotally connected therewith; a coupling-hook pivoted to the stem and adapted to swing relatively to the head; a shaft rotatably mounted in the head; a screw-cam on the shaft engaging the shank of the hook forward of the pivot; and means for rotating the shaft, substantially as and for the purpose set forth. 110

21. The combination, in a car-coupling, of a stem; a buffer-head pivotally connected therewith; a coupling-hook pivoted to the stem and adapted to swing relatively to the head; a shaft mounted to rotate in the head; a screw-cam on the shaft adapted to engage the hook and withdraw it; a stop on the head; a projection on the shaft adapted to engage the stop and lock the hook in its uncoupling position; and means for rotating the shaft, substantially as and for the purpose set forth. 115

22. The combination, in a car-coupling, of a stem, a buffer-head pivotally connected therewith; a coupling-hook pivoted to the stem and adapted to swing relatively to the head; a shaft mounted to rotate in the head; a screw-cam on the shaft adapted to engage the hook 120

and withdraw it; a stop on the head; a projection on the shaft adapted to engage the stop and lock the hook in its uncoupling position; a shoulder on the shaft arranged in close proximity to the hook, when the latter is locked in its uncoupling position, so that a slight movement of the hook will dislodge

the projection from the stop, and means for rotating the shaft, substantially as and for the purpose set forth.
